UNITED STATES PATENT OFFICE.

EUGENE H. RICHARDS, OF BOSTON, MASSACHUSETTS, ASSIGNOR TO THE
REGULAR ARMY AND NAVY UNION OF OHIO.

DESIGN FOR A BADGE.

SPECIFICATION forming part of Design No. 21,641, dated June 21, 1892.

Application filed April 21, 1892. Serial No. 430,135. Term of patent 3½ years.

To all whom it may concern:

Be it known that I, EUGENE H. RICHARDS, a citizen of the United States, residing at Boston, in the county of Suffolk, State of Massachusetts, have invented a new and original Design for a Badge, of which the following is a specification, reference being had to the accompanying drawing, forming part thereof.

The drawing represents my newly-designed badge or button.

My design for badge consists, essentially, of the representation of an eagle *e* and an anchor *f*, displayed upon a circular medallion *a*, the medallion in turn being represented as placed

in the center of the star *b*, the points *c* of the star projecting beyond the medallion, several stars *d* being also arranged about and within the circumference of the medallion.

I claim—

The design for a badge, substantially as herein shown and described.

In testimony whereof I have signed my name to this specification in the presence of two subscribing witnesses.

EUGENE H. RICHARDS.

Witnesses:

FREDERICK L. EMERY,
FRANCES M. NOBLE.
